PROPELLER

Clifford Norman Taylor, Fargo, N. Dak., assignor
to Outboard, Marine and Manufacturing Com-
pany, Waukegan, Ill., a corporation of Delaware

Application November 20, 1939, Serial No. 305,246

14 Claims. (Cl. 170—164)

This invention relates to improvements in propellers with particular reference to marine propellers.

It is the object of the invention to provide a novel, simple propeller self-adjusting as to pitch, which will remain at minimum pitch when the torque upon it is low and will adjust itself to normal, maximum pitch as the torque is increased, the construction being such that the propeller can be manufactured economically and will operate with little or no trouble from weeds.

Other objects will appear more fully in connection with the following disclosure of the invention.

In the drawing:

Fig. 1 is a rear elevation of a propeller embodying the invention.

Fig. 2 is a side elevation of the propeller as viewed from the right of Fig. 1.

Fig. 3 is a view taken in section on the line 3—3 of Fig. 1.

Like parts are identified by the same reference characters throughout the several views.

The hub 5 has the conventional bore 6 and counterbore 7 to receive the propeller shaft. At either side of bore 5, the hub is pierced by holes 8 in which the pintle pins 8 are held by set screws 9 to provide fulcrums for the blades 10. The portions of the hub 5 through which the pintles 8 extend have flat sides 11 beyond which the pintles 8 project and against which the arms 15 and 16 of the respective blades bear.

The blades 10 are identical castings. Each has a root portion encircling the narrow side of the hub and provided with spaced arms 15 and 16 between which the flattened portion of the hub is received. In each case, the trailing edge of the blade is located adjacent the projected axis of the pintle so that the major portion of the water engaging face of the blade is located forwardly of the pintle and the leading edge is remote from the pintle. The blade proper has a general direction of extent laterally from its root element, the blade center line being obliquely inclined with respect to the pintle axis as clearly appears in Fig. 1.

As best shown in Fig. 2, the arms of the respective blades have complementary cam or tooth portions which interact to require that the blades move in unison about their respective fulcrums.

In all positions of the blades, their complementary arms are loosely nested together and the contours of their opposed margins are such that in effect each of the arms 16 has a tooth at 17 fitted between rounded teeth 18 and 19 of the

arm 15 of the other blade. Consequently, when one blade is rocked from the full line position to the dotted line position shown in Fig. 2, the other blade rocks through a corresponding change of angular position so that at all times the two blades have identical pitch adjustments.

In assembling the blades on the hub, compression springs 20 are inserted between each blade and a shoulder of the hub as shown in Fig. 3.

These springs exert their pressure in a direction to maintain the blades in the position of minimum pitch adjustment shown in Fig. 1 and Fig. 2. This position is defined by engagement of the type 21 of arm 16 of one blade with the rounded

“tooth” 18 of the arm 15 of the other blade. In practice, the compression of spring 20 will be sufficient to maintain the blades in their position of minimum pitch adjustment whenever the motor which drives the propeller shaft upon which hub 5 is mounted is idling or operating at a predetermined reduced speed. When the speed of the motor is increased, thereby increasing the torque to which the blades are subject, the fact that the greatest portion of the area of each blade is ahead of the pintle 8 will cause the thrust to be exerted on the blade in opposition to spring 20 with the result that when the torque is increased to a sufficient value, the blades will simultaneously move to their position of maximum pitch adjustment as determined by the engagement of the end 22 of the arm 15 of each blade with the rounded portion 23 of the arm 16 of the other blade. The propeller is now adjusted to a position for maximum thrust to use the entire power developed by the engine in its higher speed of operation.

Since the blades are identical, only two castings are required and the springs, pintles and set screws are the only parts used in the assembly. The outlines are so streamlined that the propeller is virtually weedless in operation.

The intermeshing contours of the tooth portions of the respective blade root elements are preferably the contours of conventional gear teeth. Because each blade is acted upon individually by its own spring and is subject to like conditions of pressure and thrust, these teeth are not subject to any substantial pressures and merely perform a regulating function.

I claim:

1. In a propeller, the combination with a laterally elongated hub provided with spaced transversely extending pintle means adjacent its respective narrow sides, of bifurcated blade root elements encircling the narrow sides of the hub

and provided with interlocking extensions projecting along the wider sides of the hub, compression springs interposed between said root elements and the narrow sides of the hub and acting on said root elements in a direction to oscillate them toward a minimum pitch position, and blades carried by the respective elements and projecting therefrom beyond the respective wider sides of the hub.

2. In a propeller, the combination with a laterally elongated hub provided with spaced transversely extending pintle means adjacent its respective narrow sides, of bifurcated blade root elements encircling the narrow sides of the hub and provided with interlocking extensions projecting along the wider sides of the hub, compression springs interposed between said root elements and the narrow sides of the hub and acting on said root elements in a direction to oscillate them toward a minimum pitch position, and blades carried by the respective elements and projecting therefrom beyond the respective wider sides of the hub, said blades having their major area disposed forwardly in the direction of propeller rotation of the respective pintle axes as extended toward the tips of the blades, whereby their thrust is opposed to said spring means to oscillate the blades and root elements toward positions of maximum pitch when a predetermined torque is developed.

3. In a self-feathering propeller, the combination with a hub, of bifurcated root elements fulcrumed to the hub and partially encircling opposite sides thereof, each of said root elements being connected to the hub at opposite sides thereof, and blades extending obliquely from the respective root elements and having trailing edges near the axes on which the root elements are fulcrumed to the hub, and leading edges remote from said axes in the direction of propeller rotation, the axes upon which the root elements are fulcrumed being approximately centered with reference to the hub and laterally offset therefrom.

4. In a propeller, the combination with a hub having a central mounting bore and transverse pintles spaced at opposite sides thereof, of blade root elements partially encircling the hub and having arms pivoted on the respective pintles and provided with directly interacting and mutually interlocking terminal portions having stop surfaces limiting the movement of the elements on their respective pintles and tooth surfaces directly intermeshing with each other to constrain the elements to concurrent pitch adjustment on said pintles, and blades carried by the perspective root elements for pitch adjustment in the movement of said elements on said pintles.

5. In a propeller, the combination with a hub having a central mounting bore and transverse pintles spaced at opposite sides thereof, of blade root elements partially encircling the hub and having arms pivoted on the respective pintles and provided with mutually interlocking terminal portions having stop surfaces limiting the movement of the elements on their respective pintles and tooth surfaces intermeshing to constrain the elements to concurrent pitch adjustment on said pintles, and blades carried by the perspective root elements for pitch adjustment in the movement of said elements on said pintles, together with spring means interposed between the hub and the respective elements and biasing said elements and blades toward positions of minimum pitch.

6. In a propeller, the combination with a hub having a central mounting bore and transverse pintles spaced at opposite sides thereof, of blade root elements partially encircling the hub and having arms pivoted on the respective pintles and provided with mutually interlocking terminal portions having stop surfaces limiting the movement of the elements on their respective pintles and tooth surfaces intermeshing to constrain the elements to concurrent pitch adjustment on said pintles, and blades carried by the perspective root elements for pitch adjustment in the movement of said elements on said pintles, together with spring means interposed between the hub and the respective elements and biasing said elements and blades toward positions of minimum pitch, said blades extending obliquely from the respective elements in opposite directions and provided with trailing edges lying near the projected axes of the respective pintles and with leading edges remote from said projected axes in the direction of propeller rotation whereby the major portion of the area of each blade is disposed forward of its axis of pitch adjustment and its thrust is opposed to said spring means.

7. In a propeller, the combination with a hub, of a plurality of blades having bifurcated arm portions at their roots partially encircling the hub and from which the respective blades project obliquely, means pivotally connecting the arm portions of each blade individually to the hub, said arm portions of the respective blades overlapping at opposite sides of the hub and being provided with gear tooth surfaces in operative mutual engagement with each other for the direct transmission of motion from the arms of one blade to the arms of another, the several blades and their respective arm portions being identical and respectively unitary.

8. In a propeller, the combination with a hub, of a plurality of blades, means pivotally connecting the blades to the hub for feathering adjustment thereon, and arms rigidly projecting from the respective blades beyond their points of respective pivotal connection with the hub and provided with complementary intermeshing means adapted for the direct transmission of motion between the arms of the respective blades for maintaining said blades in synchronism as to their change of pitch adjustment.

9. In a propeller, the combination with a hub, of a plurality of identical blades provided individually with pivotal connections to the hub upon which said blades are adapted to move for pitch adjustment, each of said identical blades being provided with first and second arms spaced to embrace the hub and projecting beyond the pivotal connection of the respective blades with the hub, the first arm of each blade having a toothed portion and the second arm of each blade having a complementary toothed portion and the toothed portion of the first arm of each blade being directly intermeshed with the complementary toothed portion of the second arm of another blade, whereby the several blades are interconnected for concurrent pitch adjustment.

10. In a propeller, the combination with a hub having opposed side bearing portions and a shaft socket therebetween, of pintle means projecting from said bearing portions at each side of said shaft socket, blades having bifurcated root portions fulcrumed on the respective pintle means and embracing said hub in operative bearing

engagement with the opposed bearing surfaces thereof, said blades projecting obliquely from their bifurcated root portions, each of the bifurcated root portions of the respective blades bearing teeth and the teeth of said blade root portions being directly intermeshed with each other at each side of said hub, whereby said blades are directly intergeared for concurrent movement about the respective pintle means.

11. In a propeller, the combination with a hub having opposed side bearing portions and a shaft socket therebetween, of pintle means projecting from said bearing portions at each side of said shaft socket, blades having bifurcated root portions fulcrummed on the respective pintle means and embracing said hub in operative bearing engagement with the opposed bearing surfaces thereof, said blades projecting obliquely from their bifurcated root portions, each of the bifurcated root portions of the respective blades bearing teeth and the teeth of said blade root portions being directly intermeshed with each other at each side of said hub, whereby said blades are directly intergeared for concurrent movement about the respective pintle means, the bifurcated root portions of the respective blades being convexly arranged and complementary to build out the sides of the propeller hub beyond the bearing surfaces thereof, whereby to provide a substantially continuous and smooth weed shedding surface.

12. A propeller comprising the combination with a hub having a shaft opening upon the axis of which said hub is rotatable, of blade fulcrum means having axes substantially parallel to each other and laterally offset and approximately centered at opposite sides of said shaft opening, and substantially identical blade members pivoted upon the respective fulcrum means and extending obliquely at an acute angle to the axes of the respective fulcrum means forwardly of such axes in the direction of hub rotation, whereby to be adapted for pitch adjustment upon the respective fulcrum means.

13. A propeller comprising the combination with a hub having a shaft opening upon the

axis of which said hub is rotatable, of blade fulcrum means having axes substantially parallel to each other at opposite sides of said shaft opening, of substantially identical blade members pivoted upon the respective fulcrum means and extending obliquely at an acute angle to the axes of the respective fulcrum means forwardly of such axes in the direction of hub rotation, whereby to be adapted for pitch adjustment upon the respective fulcrum means, said blade members having blade root elements disposed laterally adjacent the hub between the respective fulcrum means at each side of the hub, and having directly intermeshing toothed portions constraining said blades to like pitch changing movement upon their respective fulcrum means.

14. A propeller comprising the combination with a hub having a central opening on the axis of which said hub is rotatable, said hub being provided with bearing faces laterally adjacent the opening and with pintle means at different sides of said opening projecting from the respective bearing faces, of identical bifurcated blade members, each provided at its root portion with spaced arms bearing on the bearing faces of the hub, each of said blades projecting obliquely from its said root portion at an acute angle to the respective pintle means upon which it is fulcrummed, the respective blades being adjustable as to pitch about their respective fulcrum means between predetermined minimum and maximum pitch positions, means on the arms of the respective blades intermeshing with each other whereby the pitch adjusting movement of the several blades is concurrent, means limiting such pitch adjusting movement, and means biasing the several blades toward said minimum pitch positions, said blades having major portions disposed forwardly of their respective axes of pitch adjustment upon said pintle means, the pressure of said biasing means being such that said blades under load are adapted to overcome said biasing means and move automatically and concurrently to said maximum pitch positions.
